UNITED STATES PATENT OFFICE.

LOUIS N. D. WILLIAMS, OF OGONTZ, PENNSYLVANIA.

TRANSFERRING DEVICE FOR KNITTED FABRICS.

1,188,124.

Specification of Letters Patent. Patented June 20, 1916.

Application filed February 13, 1914. Serial No. 818,464.

To all whom it may concern:

Be it known that I, LOUIS N. D. WILLIAMS, a citizen of the United States, residing in Ogontz, Pennsylvania, have invented 5 certain Improvements in Transferring Devices for Knitted Fabrics, of which the following is a specification.

The object of my invention is to so construct knitting machine needles and transfer points as to facilitate the transfer of 10 stitches from the needles and aid in the retention of stitches on the points after the transfer. This object I attain in the manner hereinafter set forth, reference being had 15 to the accompanying drawing, in which—

Figure 1 is a perspective view, on an enlarged scale, of a knitting machine needle constructed in accordance with my invention; Fig. 2 is a sectional view of part of 20 the cylinder or other needle carrier of a knitting machine and a side view of my improved needle therein, in the position which it assumes during the knitting operation; Fig. 3 is a similar view but illustrating the 25 needle in the position which it assumes during the transfer operation, and showing a transfer point applied to the needle and stitch; Figs. 4 and 5 are views similar to Figs. 2 and 3, respectively, but illustrating 30 another type of needle embodying my invention; Fig. 6 is an enlarged sectional view showing one stage in the act of transferring a stitch to the point; Fig. 7 is a similar view illustrating a subsequent stage in 35 the transfer; Fig. 8 is an enlarged front view of part of the transfer point, and Fig. 9 is a horizontal section on the line *a—a*, Fig. 8.

The upper portion 1 of the needle shank 40 is relatively thin but the lower portion 2 is thickened in respect to the upper portion, the thickening being at the rear of the shank and the thickened portion being grooved at its upper end so as to form a pocket 3.

45 During the operation of knitting the reduced upper portion 1 of each needle shank plays in a groove 5 at the upper end of the needle cylinder, and with a needle of the type shown in Figs. 1, 2 and 3, said groove 50 is shallower than the groove 6 which receives the thickened lower portion 2 of the needle shank, the difference in the depth of the grooves being equal to the difference

in the thickness of the upper and lower portions of the needle shank.

When it is desired to transfer stitches from the needles to transfer points, the needles are lifted so as to cause their thickened portions to project above the shallow grooves 5, the grooved upper ends of the thickened shanks entering the stitches upon the needles and the beveled shoulders 4 at the upper ends of said thickened portions serving to spread the stitches over the pockets 3, and thus facilitate the entry into said 55 stitches of the reduced ends 7 of the transfer points which are inserted behind the needles and enter the pockets therein, as shown in Fig. 6, whereby, on the descent 60 of the needles, the stitches will be cast therefrom onto the reduced ends of the transfer points and the web will be transferred stitch by stitch from the needles onto the points without risk of missing any of the stitches. When the stitches have been thus transferred, and while they are still resting upon 65 the top of the needle cylinder, needle bar, or other needle carrier, the point ring or other point carrier is depressed, as shown in Fig. 7, and thereby causes the stitches to 70 slip onto the grooved and thickened portions 8 of the transfer points which fill the stitches, and, by friction thereon, prevent them from slipping from the points as the latter are withdrawn, with the web, from 75 the machine.

The needle shown in Figs. 4 and 5 differs from that shown in Figs. 2 and 3 in that the back of the reduced upper shank 1^a of the needle, instead of being in a vertical 80 plane parallel with the back of the thickened portion 2^a of the shank, is inclined in respect to the latter, so that the back of the hooked upper end of the needle will be in the same plane as the back of the thickened 85 shank 2^a, the upper grooves 5^a of the needle cylinder in this case being of the same depth as the lower grooves 6.

The pockets 3 of the needles are adapted to receive the hooks of the dial needles in 90 that class of machines in which stitches are transferred from certain of a set of cylinder needles to corresponding dial needles in changing from plain to rib web.

I claim: 95
A knitting machine needle having the

lower portion of its shank thickened at the rear, and said thickened portion being grooved, in combination with a stitch transferring quill having a reduced point for entering the groove in the thickened portion of the needle shank, and a grooved body having side walls which overlap the upper and smaller portion of the needle shank.

In testimony whereof, I have signed my name to this specification, in the presence of two subscribing witnesses.

LOUIS N. D. WILLIAMS.
